UNITED STATES PATENT OFFICE.

JOHN ERICKSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE RECEIVER.

Application filed August 10, 1923. Serial No. 656,668.

The present invention relates to telephone receivers in general, but is concerned more particularly with loud speaking telephone receivers; and the broad general object is the 5 production of a new and improved "loud speaker" comprising a new and improved loud speaking telephone receiver together with the container and the necessary associated parts, all of which are of exceedingly 10 simple design and of rugged construction.

Another object is to so design the receiver and its container that the receiver can be mounted conveniently therein.

A further feature of novelty resides in the 15 arrangement of a flange, located at the mouth of the container, against which the receiver fits on one side and against which the base of the horn fits on the other side so as to make a good connection between the 20 two without the possibility of the receiver being jarred unduly or forced out of adjustment when the horn is placed in position.

Another object of the invention is the production of a new and improved mechanical 25 construction whereby the soft iron pole pieces and the permanent magnet of the receiver cooperate to make a low reluctance magnetic path to the ends of the soft iron pole pieces.

30 A further feature of improvement is the provision of an adjusting screw whereby one of the soft iron pole pieces may be raised or lowered as the case may demand, in order to bring its surface on the line with the surface of the other pole piece. This enables 35 the slight mechanical imperfections which arise during manufacture to be compensated for.

40 A further feature of novelty relates to the improved adjusting means whereby the distance between the pole pieces and diaphragm may be varied at will.

45 A further feature of novelty resides in the improved friction device which retains the turnable mounting plate of the receiver rigidly in any position in which it is placed by the adjusting device.

50 A still further feature of novelty resides in the improved truss diaphragm which consists of two thin diaphragms clamped together at the edges and held slightly apart at the center.

There are various other minor features of improvement which will be brought out in the detailed description which is to follow. 55

Referring now to the drawings comprising Figs. 1-7, inclusive, which show one mechanical embodiment of the new and improved loud speaking receiver, Fig. 1 is a complete reduced size rear view of the improved loud speaker.

Fig. 2 is a full sized drawing of the loud speaker with the upper part of the horn cut away and with the device in the position of Fig. 1. This view, it may be stated, is partly 60 a cross section through the centre of the device and is partly an elevation.

Fig. 3 is a cross section through the centre drawn at right angles to the plane of the paper on which Fig. 1 is drawn, and is 70 drawn with the loud speaker held in the position of Fig. 1 and as seen when looking in the direction of the arrow A.

Fig. 4 is a bottom view of the loud speaker with the base and the transformer removed. In this view, the rear of the loud speaker is at the bottom and the front is at 75 the top.

Fig. 5 is a top view of the loud speaking receiver with the diaphragm and the cap 33 80 removed and with certain parts cut away to give a better view of the parts underneath. The front part of the receiver is shown at the top and the rest at the bottom.

Fig. 6 is a side elevation of the improved 85 diaphragm as it appears before being clamped in place in the receiver.

Fig. 7 is a cross section through the adjusting member 46 and the spring 47, together with a section of the container 2, and is drawn on the line XX, Fig. 3, as seen from above.

The construction of the improved loud speaker will be now explained a little more in detail. The parts are so designed that 95 the receiver, which comprises the cylindrical shell 19, Figs. 2 and 3, together with its contents and the compound diaphragm and the cap, may be mounted inside the container 2 after the said parts have been properly assembled as follows: The diaphragm shown in Fig. 6 is placed upon the shell 19 and is clamped between the shell and the cap 33 by means of the screws 51 and 52, Fig. 2, 53 and

54, Fig. 3, and others which are not shown. The diaphragm when thus clamped assumes the position shown in Figs. 2 and 3.

The remaining elements of the receiver may

- 5 next be assembled on the plate 21. The connecting posts 25 and 45, when assembled, extend perpendicularly through the plate as may be seen best in Fig. 3. These posts it may be seen, are securely clamped to the 10 plate 21 and are insulated therefrom. For example, the post 25 fits inside the insulating jacket 60, being thereby insulated from the plate 21. The metal washer 28, which is engaged by the shoulder of binding post 25, 15 is insulated from the plate 21 by the insulating washer 59, and the nut 26 is insulated from the plate 21 by the piece of insulation 27, whose shape may be seen most clearly in Fig. 5.

- 20 The permanent magnet 22 may next be placed in position and is held by means of the machine screws 60 and 61, Figs. 4 and 5, and the nuts 62 and 63, Fig. 5.

- 25 The adjusting screw 64, Figs. 2, 4 and 5, may next be screwed in until the end thereof is flush with the top of the plate 21, as shown in Fig. 2.

- 30 The two soft iron pole pieces 23 and 24 on which the windings 29 and 30, Fig. 2, have previously been placed may next be placed in the position most clearly shown in Fig. 5. As may be seen in Fig. 3, the pole piece 24 rests on a foot or extension at either end. The pole piece 23 is made in the same way. 35 The feet of the soft iron pole pieces which are beneath the bobbins 29 and 30 are placed in a pair of notches in the insulated member 27, one of which may be seen in Fig. 5, directly over the end of the adjusting screw 64.

- 40 The spreading member 50 may next be dropped into place between the outer ends of the soft iron pole pieces. The washer 49 is next placed over the said spreading member 50, after which the screw 48 is placed in position and screwed down so as to hold the entire assembly together. The screw 48 is not turned tightly at first and the adjusting screw 64 is turned in or out in order to bring the tops of the pole piece 24 even with the top of the pole piece 23. This adjustment obviates the necessity of the usual practice of grinding down the magnets after the assembly is complete. Otherwise, the grinding down process is practically a necessity due to mechanical imperfections in manufacture, and the attempt to level up the pole pieces in this manner results in fine particles of iron clinging to the pole pieces which can be removed only with difficulty. It is frequently the case that one or more small particles of iron are left clinging to the pole pieces which, as is well known, greatly impairs the efficiency of the receiver. 65 The grinding down process is further objec-

tionable as it often hardens the surface of the iron thereby making it less permeable. In this case, however, since the above mentioned means is provided for bringing one pole piece to the same height as the other, no grinding down process is necessary for that purpose.

70 After the pole pieces have been leveled up by means of the adjusting screw 64, the spreading member 50, which has a hexagonal top, and which is approximately oval at the bottom, is turned to the right in order to force the pole pieces 23 and 24 tightly against the ends of the permanent magnet 22. The member 50 assumes approximately 75 the position shown in Fig. 5. The screw 48 is now turned tightly to hold the parts in place.

80 The combined adjusting segment and clamping member 20 which can be seen most clearly in Fig. 4 is next screwed onto the plate 21 by means of the screws 57 and 58. The main part of the member 20 is spaced from the plate 21 by means of the washers 81 and 82, while the arms 83 and 84 press 85 firmly against the plate 21 due to having been tensioned previously.

85 The plate 21 with the parts assembled thereon as described above is next screwed into the shell 19 as shown in Figs. 2 and 3. 90 Before the soft iron pole pieces have reached the diaphragm, the plate 21 comes flush with the bottom of the shell 19, and as the plate 21 is turned in still further, the arms 83 and 84 slide along and press against the shell 19 95 and are left behind by the plate 21, these arms serving to hold the plate 21 rigidly in any position in which it is left.

100 The plate 21 and its assembly are turned still further until the diaphragm is "seized" 105 by the pole pieces which manifests itself by a faint but sharp click. The plate 21 is then backed off just enough to permit the diaphragm to be released. The receiver is now completely assembled and is ready to 110 be placed in the container.

115 In order to prepare the container 2 for the reception of the receiver and the horn, the rubber gaskets 34 and 36, Figs. 2 and 3, are placed in position on either side of the flange 35 in the throat of the container 2.

120 It now remains only to place the adjusting member 46 and its retaining spring 47 into position, the said spring fitting into a suitable groove in the adjusting member 46, 125 as may be seen in Figs. 3 and 7. The principal function of the spring 47 is to hold the member 46 tight to prevent it from rattling and giving off undesirable sounds when the loud speaker is in operation.

130 The receiver, having been assembled and having received its preliminary adjustment as described above, is now placed in the container in the position indicated in Figs. 2, 3, and 4, with the exception that the adjusting

- segment 20 is not in the same position relative to the adjusting member when the receiver is first placed in the container, on account of the fact that it is shown in Fig. 4 as having already been finally adjusted in accordance with a particular desired volume. Instead, when the receiver is first placed in the container, the left hand edge of the segment 20 is all the way around to the left and lies against the edge of the washer 18. Accordingly the only adjustment that can be made from this position is one which brings the pole pieces still farther away from the diaphragm. This is desirable on account of the fact, as above stated, the pole pieces are already adjusted as close to the diaphragm as they can be placed without an actual seizure of the diaphragm.
- 20 In order to hold the receiver in place, the washers 17 and 18 are placed in position, after which the bolts 13 and 14, Figs. 2 and 4, are screwed in tightly thereby clamping the shell 19 in place, leaving the plate 21 with its attached parts free to turn inside the shell 19 except for friction which is made considerable by the pressure of the arms 83 and 84 against the bottom of the shell 19.
- The transformer and its mounting may be next assembled. The terminal mounting strip 43, Figs. 2 and 3, has four screw terminals mounted thereon, as shown in Fig. 2. Two of these are used as terminals for the incoming flexible two conductor cord, and the other two are used as terminals for the wire leading from the secondary of the transformer to the receiver. The terminal mounting strip 43 and the laminated transformer core 40, together with the two spacing sleeves 41 and 42 are clamped to the bracket 12 by means of the two machine screws 37 and 38, which cooperate with threaded holes in the bracket 12. Fig. 3 shows a cross section of the primary and secondary windings of the transformer which are both indicated by the reference numeral 39. There is a spacer 44 which may be composed of any insulating material and which is used to enlarge the air portion of the core surrounding the iron core in order to permit the higher voice frequencies and the various high frequency harmonics to pass through the transformer with more facility.
- 55 The transformer having been mounted thereon, the bracket 12 may be fastened to the ends of the hexagonal mounting bolts 13 and 14 which for this purpose are threaded to receive the screws 15 and 16, Fig. 2.
- 60 The next step in the assembly is the connecting up of the primary and secondary leads (not shown) of the transformer to the four lugs of the terminal mounting strip 43, Fig. 2. The two terminals to which the secondary windings of the transformer are connected are next connected by means of a pair of wires (not shown) to the terminals 45 and 25 of the receiver, which terminals may be seen best in Figs. 3 and 4. These wires, it may be stated, are preferably soldered to the terminals 45 and 25 while they may be fastened to the binding strip 43 by means of screws thereon. It now remains to bring the flexible two conductor cord (not shown) in through the hole 7, Figs. 1, 3 and 4, in the container 2 and connect it under the two remaining screws in the terminal strip 43.
- The base 9 together with the felt cover 8 and the iron retaining ring 10, Figs. 2 and 3, may now be secured to the container by means of the screw 11 which passes through a hole in the felt covering of the base 9 and through a hole in the base 9 and is screwed into a threaded hole in the transformer mounting bracket 12.
- In order to complete the assembly it is only necessary to insert the metal tip 4 of the horn 3 in the hole in the top of the container 2, so that the metal tip 4 rests on the rubber gasket 36, after which the screw 5 is tightened to hold the horn in the position of Fig. 1.
- The loud speaker may now be connected in a suitable circuit and the final adjustment of the distance between the diaphragm and the pole pieces is then made. This is accomplished by inserting an ordinary screw driver or a similar device into the slot in the head of the adjusting member 46, Fig. 3, after which the member may be turned the correct amount to bring the receiver into the proper position to give it the desired space between the pole pieces and the diaphragm. For the average case the position indicated in Fig. 4 is about correct. It may be pointed out that it is impossible to injure the receiver by turning the adjuster too far in either direction, the segment 20 striking either the washer 17 or the washer 18 before the member can be turned too far.
- A few of the more prominent features of the improved loud speaker will now be discussed from the standpoint of utility. It has been known for many years that a good telephone receiver is one of minimum weight and maximum rigidity. The minimum weight permits the diaphragm to be vibrated with a minimum expenditure of energy, while great rigidity permits it to be brought very close to the pole pieces without being "seized". In the past numerous diaphragms have been constructed of various diameters and of various thicknesses and shapes in order to attain the end above set forth. These attempts have led to a fair degree of success for telephone receivers handling moderate amounts of energy, but have not heretofore been completely successful as concerns loud speaking telephone receivers wherein the

diaphragm in vibrating comes very close to the pole pieces. It is obvious, however, that the truss diaphragm disclosed in this application combines maximum rigidity

- 5 with minimum weight on account of its hollow interior. Furthermore, it has been found that the weight of the diaphragm has been decreased sufficiently to permit the weight of an extra soft iron armature to be
 10 added to the diaphragm at the centre in order to decrease the reluctance of the magnetic circuit.

This truss diaphragm may be seen in Figs. 2, 5, and 6, and comprises the separate thin
 15 discs 31 and 32, the soft iron armature 55, the rivet 56 and the washer 51. The discs 31 and 32 are preferably punched from tin plated steel although any other desired metal or substance may be used.

- 20 As an alternative the soft iron washer 55 may be placed below the lower diaphragm 32 in which case the pole pieces 23 and 24 are suitably shortened and a sleeve spacer may be used around the rivet 56 in order to
 25 hold the discs apart in the centre in the absence of washer 55. This construction, although somewhat more complicated from a mechanical standpoint, has the added advantage of a still shorter magnetic path
 30 which may be found desirable in certain cases.

Regarding the construction of the receiver itself it will be noted that the pole pieces 23 and 24 lie snugly against the ends of the
 35 permanent magnet 22 as may be seen in Figs. 3 and 5, and are both held in position by the single screw 48. This construction serves the double purpose of making the receiver simple to manufacture and easy to assemble
 40 and also makes a very good connection between the magnet and the pole pieces, resulting in a low reluctance path and consequently a high flux density at the ends of the pole pieces, this being especially desirable
 45 for any loud speaking telephone receiver.

Regarding the arrangement for adjusting the distance between the pole pieces and diaphragm while the device is in actual operation, it may be pointed out that this is especially desired on account of the great difference in the amount of volume desired by the various users of such a device. Some users prefer the loud speaker to operate with a large volume of sound and accordingly use a large amount of amplification in order to attain this end. When this is done the diaphragm must of necessity be at some distance away from the pole pieces so that it will not strike the latter in vibrating. On the other hand, many users desire a relatively small volume of sound and may therefore dispense with much of the amplification which would otherwise be used. When this is done the receiver works most efficiently with the diaphragm fairly close to the

pole pieces. Either of these conditions may be met by merely turning the adjusting member 46 shown in the drawings.

What I claim is:

1. In a telephone receiver, a pair of pole pieces disposed in parallel planes, and means for adjusting the position of one in its plane and relative to the position of the other pole piece.

2. In a telephone receiver, a magnet having its poles formed into two substantially parallel faces, two soft iron pole pieces fitted against said faces, a single screw holding said pole pieces in position, and a hollow non-circular member through which said screw passes and which may be turned to force said pole pieces snugly up against said faces.

3. In telephone receiving device, a diaphragm, a receiver assembly and a diaphragm assembly, said receiver assembly having a base with screw threads thereon, said diaphragm assembly being provided with a threaded hole into which said receiver assembly may be screwed so as to bring it into operative relation with said diaphragm, means for adjusting the distance between one of said poles and said diaphragm, and means including toothed gears for subsequently turning said receiver assembly back and forth to adjust the distance between said receiver assembly and said diaphragm.

4. In a telephone receiving device, a diaphragm, a receiver assembly and a diaphragm assembly, said receiver assembly having a base with screw threads thereon, said diaphragm assembly being provided with a threaded hole into which said receiver assembly may be screwed so as to bring it into operative relation with said diaphragm, means including toothed gears for subsequently turning said receiver assembly back and forth to adjust the distance between said receiver assembly and said diaphragm, and a friction device attached to and rotatable with said receiver assembly and bearing against said diaphragm assembly to maintain the adjusted position of said parts.

5. In a telephone receiving device, a diaphragm assembly and a receiver assembly containing two pole pieces disposed in parallel planes, means for adjusting one of said pole pieces in its plane and with respect to the other pole piece, and means for adjusting said receiver assembly with respect to said diaphragm.

6. In a telephone receiving device, a diaphragm assembly and a receiver assembly, a plurality of pole pieces on said receiver assembly, means for adjusting one of said pole pieces with respect to said diaphragm, and means for adjusting said receiver assembly with respect to said diaphragm.

7. In a telephone receiving device, a diaphragm assembly and a receiver assembly,

- said receiver containing a plurality of pole pieces, said diaphragm assembly including a two member diaphragm, the members of which are clamped together at the outer edges and spaced apart at the center, means for adjusting the distance between one of said pole pieces and said diaphragm, and means for adjusting said receiver assembly with respect to said diaphragm.
8. In a telephone receiver, a diaphragm, a pair of pole pieces disposed in planes parallel to the axis of said diaphragm, means for moving one of said pole pieces in its plane without altering its relation to said axis, and means for moving both of said pole pieces without altering their relation to said axis.
9. In a telephone receiver, a permanent magnet having pole faces in substantially parallel planes, soft iron pole pieces fitted to said faces and lying in planes parallel to said first planes, means comprising a non-magnetic cam shaped clamping member for holding said pole pieces against said faces and means for then moving one of said pole pieces for a limited distance within its plane without disturbing said clamping means.

In witness whereof, I hereunto subscribe my name this 8th day of August, A. D., 1923.

JOHN ERICKSON.
